US00D356996S

United States Patent [19]

Henderson et al.

[11] Patent Number: Des. 356,996

[45] Date of Patent: ** Apr. 4, 1995

[54] POWER MODULE

- [75] Inventors: **Harold A. Henderson**, Los Gatos; **Howard A. Powers**, Scotts Valley, both of Calif.
- [73] Assignee: **VLT Corporation**, San Antonio, Tex.
- [**] Term: **14 Years**
- [21] Appl. No.: **21,210**
- [22] Filed: **Apr. 12, 1994**

Related U.S. Application Data

- [63] Continuation of Ser. No. 3,204, Jan. 5, 1993, abandoned.
- [52] U.S. Cl. **D13/110**
- [58] Field of Search **D13/110; 361/679, 688, 361/690, 707, 709, 715, 728, 730; 363/141**
